[57] CLAIM

The ornamental design for a safety light for vehicles, as shown and described.

DESCRIPTION

FIG. 1 is a top, front perspective view of a safety light for vehicles showing my new design;

FIG. 2 is a front elevational view thereof on a reduced scale;

FIG. 3 is a side elevational view thereof on a reduced scale;

FIG. 4 is a rear elevational view thereof on a reduced scale;

FIG. 5 is a bottom plan view thereof on a reduced scale. The lens is shaded to indicate translucency.

FIG. I

FIG. 2

FIG. 3

FIG. 4

FIG. 5
